UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

PAPER-PERFORATING MACHINE.

SPECIFICATION forming part of Letters Patent No. 599,560, dated February 22, 1898.

Application filed September 17, 1897. Serial No. 652,024. (No model.)

To all whom it may concern:

Be it known that I, FREDERICK W. HEDGELAND, a citizen of the United States, residing in Chicago, in the county of Cook and State of Illinois, have invented a new and useful Improvement in Paper-Perforating Machines, of which the following is a specification.

This invention relates more especially to perforating-machines for perforating the music-sheets used in self-playing instruments. It may, however, be used for perforating paper for other uses.

The main feature of the invention lies in the mechanism employed for operating the punches. The stems of the punches are made extensible, preferably by inserting in them or adding to them a toggle the normal position of which is one of contraction, and the toggles are expanded or straightened by the action of an electromagnet whenever the punches are to be operated. The straightening of the toggles lengthens the stems, so as to throw the upper end thereof into the path of a rapidly-rotating cam extending across the series of punches and acting to force the lengthened ones downward and cause them to operate before their toggles can relax. After the operation the punches are raised from the paper by a lifting device, also common to all punches, and operated at each revolution of the cam-shaft, and the toggles are contracted by suitable springs. By this construction I obtain such rapid action by the punches as enables me to feed the paper continuously and to obtain the very best results both in the quality of the work and the ease and rapidity with which it is done.

The nature of the invention is fully disclosed below and will be understood from the accompanying drawings, in which—

Figure 1 is a front elevation of the machine, and Fig. 2 is a section on the line 2 2 of Fig. 1. Fig. 3 is a detail showing the connection between one of the toggles and its magnet.

In said drawings, A A represent the end uprights of the machine, by which most of the parts are supported. They are connected by cross-bars A', A², A³, and A⁴, located as shown, and by table B, over which the paper W is drawn by the take-up roll C, continuously driven by suitable mechanism. (Not shown.)

D D are the punches. They are arranged in a straight line transverse of the machine and in such number as the work requires. They work vertically in guides D' D² D³ D⁴. 55 The toggles are shown at D⁵ and are located between the ends of the punches, the main portion thereof being below and the extremities D⁶ being above the toggles. The normal condition of these toggles is indicated at Fig. 60 2 by full lines and is one of contraction, while the extended position is shown by the broken lines in the same figure. In the latter position the upper extremities D⁶ of the several punches are raised sufficiently to bring them 65 into the path of a cam E upon the shaft E', journaled in the uprights A and rapidly driven by the pulley E² and so the punches will receive a downward thrust from said cam. This cam-shaft extends over the entire series 70 of punches and operates any of them which may be extended. The downward thrust thus imparted to the punches causes them to perforate the paper. A stop D⁷ limits the upward movement of the upper part D⁶ of the stems 75 by encountering the shoulders D⁸ upon the stems. A balance-wheel E³ is preferably employed on the shaft E'.

To bring about the straightening of the toggles and the lengthening of the punch-stems, 80 each toggle is connected to a separate actuating device under the control of a sample music-sheet or of the musical instrument, the playing upon which is to be recorded in the sheet being perforated. I show a suitable 85 form of the actuating device, but the connections between it and the sample music-sheet or the instrument whose playing is recorded are not shown, as they form no part of the present invention, and are, moreover, well 90 known to those skilled in the art. In my preferred construction the actuating device is an electromagnet F, the armature F' of which is made in the form of a rocking elbow-lever and the vertical member of which is connected 95 to the toggle to which it belongs by a wire tie F², as shown. The energizing of the magnet rocks the armature and thereby draws the toggle to its extended position, as shown by the broken lines in the case of one of the toggles in Fig. 2. In order to compact the machine as much as possible, I arrange the se-

ries of magnets in four rows—two rows in front and two behind the punches—and invert some of them, as illustrated, and I also bring the operating ends of the armatures all 5 to the same level, so that they may draw directly and to good advantage upon the toggles.

To shorten the toggles after the magnets have ceased action thereon, springs G are attached one to each armature and act thereon 10 in a direction opposed to the magnets. The springs are of course of little strength, so the magnets may readily overcome them.

After each perforating operation the punches are lifted out of the paper by suitable means—such, for instance, as the rocking lifter H, consisting of a wide bar extending across the series of punches and engaging the pins H', inserted therein. This bar or lifter is pivoted at its ends at H² and is rocked 15 constantly and rapidly by the eccentrics H³ upon each end of the cam-shaft and the connecting-arms H⁴. A weight H⁵ is preferably attached to the lifting-bar H, outside of the pivots H², to balance the weight of the acting 20 edge of the lifter, in order that the lifter may be easily operated and not jar the machine. The eccentrics are arranged so as to cause the lifter to rise immediately after the cam has depressed the punches, whose toggles are 25 straightened, and consequently the punches are withdrawn from the paper instantly upon the completion of the perforation, so that they do not interfere with the continuous feeding of the paper and, indeed, allow the paper to 30 be fed at a much greater speed than has heretofore been possible. A guide L, immediately over the table and close to the line along which the perforations are made, prevents any lifting 35 of the paper with the punches as they move 40 upward. The table B along said line is provided with openings B', having cutting edges and giving room for the punches to descend through the paper.

The operation of the machine is as follows:

45 The shaft E' and the take-up roll C being both set in motion by suitable driving mechanism and the magnets being also electrically connected to the devices, so that the music-sheet being reproduced or the instrument being 50 played may control them, the magnets corresponding to the keys or notes which are to be represented in the sheet being perforated as being sounded are energized and their armatures are operated, so that the toggles of the punches corresponding to the energized magnets are straightened, thereby 55 extending the stems of those punches and insuring their being operated in perforating the paper as soon as the cam E encounters them.

60 As the cam is rapidly moving it follows that the perforations are made almost instantly and before any relaxation of the toggles. The punches are also retracted instantly afterward by the lifter, which rises with every 65 revolution of the cam-shaft. In the case of long notes the perforations are repeated and so close together as to form continuous open-

ings, the magnets remaining energized so long as the notes sound and thus retaining the toggles in their expanded positions for the same 70 length of time, and while this condition obtains the punches will be alternately depressed and lifted by the cam and lifter. The springs cause the relaxing of the toggles whenever the magnets are cut out of circuit, being 75 assisted in that operation by the lifter.

I claim—

1. The combination in a paper-perforating machine, of punches each embodying between its ends a toggle D⁵, means for straightening 80 said toggles, means for lifting the punches and a rapidly-moving cam acting upon the upper ends of the punches when the toggles are straightened, substantially as specified.

2. The combination in a paper-perforating 85 machine, of punches made extensible, toggles for extending said punches, a rapidly-moving cam for operating the punches while extended, and means independent of said toggles for withdrawing the punches from the paper, sub- 90 stantially as specified.

3. The combination in a paper-perforating machine, of a series of extensible punches, a rapidly-rotating cam having no attachment 95 to the punches and acting to depress the extended ones, and means for lifting the punches out of the paper, substantially as specified.

4. The combination in a paper-perforating machine, of a series of punches each provided with a toggle whereby it may be lengthened 100 and shortened, a rapidly-moving cam for operating the punches, a rapidly-operating lifter for retracting the punches, and means for controlling the toggles, substantially as specified. 105

5. The combination in a paper-perforating machine, of a series of punches each provided with a toggle whereby it may be lengthened and shortened, a rapidly-moving cam for operating the punches, a rapidly-operating lifter for retracting the punches, and magnets for controlling the toggles, substantially as specified. 110

6. The combination in a paper-perforating machine, of a series of punches each provided with a toggle whereby it may be lengthened and shortened, a rapidly-moving cam for operating the punches, a rapidly-operating lifter for retracting the punches, magnets for straightening the toggles, and springs for contracting the toggles, substantially as specified. 115

7. The combination in a paper-perforating machine, of a series of punches having toggles, a cam operating all the punches, a lifter for raising the punches after operation, a magnet for each punch having its armature connected to the toggle thereof, and a spring for each punch acting contrary to the magnet, substantially as specified. 120
